PITMAN OR LIKE MACHINE ELEMENT

Charles J. Hudson, Eldorado, Kans.

Application August 10, 1938, Serial No. 224,158

6 Claims. (Cl. 74—589)

This invention relates to machine elements such as pitmans and more particularly to pitmans constructed or equipped to counterbalance the weight of associated machine elements.

Although machine elements embodying the invention may be used advantageously in machines of various kinds, they may be used to particular advantage in pumping machinery, for example, such as is used in the oil fields. Oil well pumps generally include a heavy pump rod connected to one end of a walking beam and a pitman connected to the other end of the walking beam and to a crank. The weight of the pump rod frequently is so great that counterweights have been applied to the walking beam to relieve the pumping machinery of the recurrent load pulsations resulting from lifting the pump rod. I have found that the strain on the pumping machinery can be eliminated still further by providing a weight for counterbalancing the pump rod and positioning the weight on the pitman adjacent the crank so that the inertia of the weight, moving in a substantially continuous orbital path, creates a fly-wheel effect which prevents the pulsating shocks inherent in counterbalancing arrangements heretofore provided.

Accordingly, one object of the invention is to provide a mechanism including a pitman and a counterweight positioned on the pitman close to its crank-connected end.

Another object is to provide a pitman or the like element equipped with a counterweight and in which a simple and positive interconnection between the element and the counterweight is provided.

A further object is to provide a pitman or like element including spaced arm parts and a weight device adapted to perform the dual function of providing a desired counterbalancing effect and at the same time reenforcing the spaced arm parts.

Other objects will become apparent from a reading of the following description, the appended claims, and the accompanying drawing, 45 in which:

Figure 1 is a view showing a pitman embodying the invention and as it may be used in one kind of pumping machinery, only parts of which are shown;

Figure 2 is a front elevational view of a pitman embodying the invention, drawn on an enlarged scale as compared to Figure 1;

Figure 3 is a partial longitudinal section taken on the line 2—2 of Figure 4;

Figure 4 is a view in edge elevation, and

Figure 5 is a detail view in elevation showing a combined balancing weight and reenforcing member.

Referring to Figure 1, a pitman A is shown connected at one of its ends to a crank B and at its other end is equipped with a stirrup C providing connection to one end of a walking beam D mounted to rock on a Sampson post E, the other end of the walking beam being connected to the usual pump rod F. The pitman includes spaced end blocks 1—2 connected by an elongated body part or arm generally designated 3 and comprising spaced parts or straps 4 and 5 secured to the blocks 1 and 2 by means of bolts 6 and 7 respectively.

The block 1 is provided with a rectangular opening 8, one end of which is formed with a semicircular seat 9 for receiving a bushing or babbittting (not shown). A movable seat member 10 is mounted for adjustment within the rectangular opening 8 and is formed with an inclined face 12 adapted to cooperate with a correspondingly inclined face on an adjusting wedge 13 adapted to be drawn into adjusted position by means of a screw 14 for holding the bushing or babbittting in place. The block 1 serves to connect the pitman to the crank arm B. The block 2 is shown as being provided with a plurality of apertures 15 which provide for connection of the pitman to the stirrup C.

In accordance with my invention, a desired balancing of the pitman, or counterbalancing of the pump rod is obtained through the provision of a weight generally designated 16 which is mounted on the arm 3. In the preferred embodiment of the invention, two weights designated 17 and 18 are shown, and it will be understood that these two weights together constitute the weight or means for effecting the desired balance of the pitman and counterbalancing of the pump rod. The weight 17 comprises a body part 17^a which is adapted to be fitted between the arm parts 4 and 5, and lugs 17^b which extend from both edges and at each end of the weight so as to lie alongside the strips 4 and 5. The opposite ends of the body part 17^a (included between adjacent lugs 17^b) are inclined and parallel.

This facilitates positioning of the weight 17 on the arm with the body 17^a included between the arm parts 4 and 5 and with the lugs 17^b lying alongside the parts 4 and 5 respectively. The weight 17 is positioned on the arm 3 by first inserting it between the straps 4 and 5 as indicated at (a) in dotted lines in Figure 3 and then tilting it, in the direction of the arrows x and y, 55

through the dotted line position (b) and finally to the position shown in full lines in Figure 3. The inclination of the ends of the body part 17^a permits this tilting movement insertion, and also 5 results in the outermost edges of the inclined ends of the body 17^a being disposed close to the associated arm parts 4 and 5 when the weight has been moved to its final position.

The weight 18 is similar in construction to the 10 weight 17^a, comprising also a body part 18^a and lugs 18^b. The weight 18 may be positioned on the arm 3 in a manner similar to that described with reference to the positioning of the weight 17. For maintaining the weights in place, set 15 screws 19 and 20 are extended through apertures 21 formed in the arm part 5 so as to bear respectively against the weights 17 and 18.

Preferably, when using two weights, they are positioned in abutting relation with the ends of the weights adjacent the arm 5 extending towards opposite ends of the arm and sloping away from the adjacent arm part 5, as shown most clearly in Figure 2. As a result of this arrangement, the set screws 19 and 20, acting on the 20 inclined ends of the weight bodies, will tend to force the weights together and prevent their separation, thereby maintaining them securely in place on the arm. It will be understood that the number or size of the weights used will 25 depend upon the balance required, and that the weights will act to reenforce and strengthen the arm structure as well as to counterbalance the weight of the pump rod.

The embodiment of the invention disclosed 30 herein is a practical and the now preferred form, but various changes may be made in the construction and relative arrangement of the parts without departing from the invention as defined in the claims.

40 I claim:

1. In a movable machine element, an arm comprising spaced substantially parallel parts; and a balancing weight including a body removably positioned between said spaced arm parts, and lugs protruding respectively from each side and at each end of said body and lying alongside the edges of said spaced arm parts, the body part and lugs being so proportioned relative to spaced arm parts, and the ends of the body part included between said lugs being so formed and proportioned as to permit angular or tilting movement of said weight in the direction of extent of said arm to facilitate removal of the weight, the body part yet having portions lying close to the respectively associated adjacent spaced arm parts when the weight is in operative position.

2. In a movable machine element, an arm comprising spaced substantially parallel parts; and

a balancing weight including a body removably positioned between said spaced arm parts, and lugs protruding respectively from each side and at each end of said body and lying alongside the edges of said spaced arm parts, the body part included between said lugs being inclined in the direction of extent of said arm and substantially mutually parallel.

3. In a movable machine element, an arm; a pair of balancing weights mounted on said arm; 10 and separate means carried by the arm at points spaced longitudinally thereof and associated separately and respectively one only with each weight for urging the weights together and resisting their separation longitudinally of the 15 arm.

4. In a movable machine element, an arm comprising spaced substantially parallel parts; two balancing weights mounted on said arm and between said spaced arm parts, the ends of each weight being inclined in the direction of extent of said arm and substantially mutually parallel, 20 the ends of one weight being inclined reversely to the ends of the other weight, the two weights being in abutting relation with two adjacent ends extending towards opposite ends of the arm and sloping away from the adjacent arm part; and set screws extending through said adjacent arm part and bearing against said last named ends, thereby urging said weights together. 25

5. In a movable machine element, an arm comprising spaced substantially parallel parts; two balancing weights mounted on said arm, each of said weights including a body positioned between said spaced arm parts and lugs protruding 30 respectively from each side and at each end of said body and lying alongside the edges of said spaced arm parts, the body part intervening between said lugs being inclined in the direction of extent of said arm and substantially mutually parallel, 35 the body ends of one weight being inclined reversely to the body ends of the other weight, the two weights being in abutting relation with two adjacent body ends extending towards opposite ends of the arm and sloping away from the adjacent arm part; and set screws extending through said adjacent arm part and bearing against said last named body ends, thereby urging said weights together. 40

6. In a pitman, spaced connecting block members formed with parallel apertures for affording connection respectively to other machine elements; a pitman arm structure comprising spaced straps extending between and connecting said block members; and a combined balancing weight 50 and reinforcing member secured to and between said straps intermediate the connection of the straps to the blocks. 55

CHARLES J. HUDSON.
